R. E. MILLER

WATER COOLER

Filed Oct. 9, 1922

Fig. 1.

Inventor:
Royal E. Miller
son of Miller Regs.

UNITED STATES PATENT OFFICE.

ROYAL E. MILLER, OF CHICAGO, ILLINOIS, ASSIGNOR TO THE ADAMS & WESTLAKE COMPANY, A CORPORATION OF ILLINOIS.

WATER COOLER.

Application filed October 9, 1922. Serial No. 593,396.

To all whom it may concern:

Be it known that I, ROYAL E. MILLER, a citizen of the United States, and resident of Chicago, county of Cook, and State of Illinois, have invented certain new and useful Improvements in Water Coolers, of which the following is a specification and which are illustrated in the accompanying drawings, forming a part thereof.

10 The invention relates to water coolers primarily designed for use in railway cars, though not necessarily limited thereto, and being of a type in which the drinking water is contained in a tank enclosed within an 15 icing chamber but disconnected therefrom in order that there may be no contamination by the ice.

10 The objects of the invention are to generally improve and simplify coolers of this 20 type, and the invention consists of a structure such as hereinafter described and illustrated in the accompanying drawings, in which—

25 Fig. 1 is a vertical central section of the cooler;

Fig. 2 is a transverse section on the line 2—2 of Fig. 1; and

Fig. 3 is a plan view of the device.

30 The cooler comprises an ice container 10 of any suitable form, being shown as cylindrical. The walls of the container may be packed with an insulating material, as indicated in Fig. 2. Its bottom 11 is preferably of wood with a metal lining, as shown at 12.

35 It is desirably entirely open at the top and provided with a removable cover or lid 13. The side walls of the container are shown as prolonged somewhat below the bottom 11, to form a closure for protecting the draw-off pipe 14, and to the extreme bottom end 40 of the container there is applied a drip pan 15 having a tray 16 for holding a glass directly below the draw-off faucet 17, and also provided with a nipple 18 which may be connected with a suitable drain pipe.

45 This container will ordinarily be mounted against a wall, and may be secured thereto by means of any suitable form of bracket.

Drip openings 19 are provided in the bottom 50 11 to permit the discharge of water resulting from the melting of the ice. These openings may be as numerous as desired, two being shown.

55 The water tank 20 is shown as cylindrical in form, and is housed within the container

10, removably fitting within a band 21 spaced apart from the container walls but rigidly secured thereto, as by means of brackets 22, which may be disposed as found desirable to secure adequate strength, but 60 are preferably so placed as to interfere as little as possible with the charging of the container with ice. A plurality of lugs 23 are attached to the walls of the tank 20, to engage the band 21, in order that it may 65 serve as a support as well as a guide for the tank. The upper end of the tank 20 is closed by a suitable cap or cover 24.

An annular wall 25 rises from the bottom 11 of the container 10 for inclosing and positioning the lower end of the tank 20. The bottom 26 of the tank is centrally apertured and provided with a flaring nipple 27, adapted to fit upon a plug 28, preferably of rubber, secured to the bottom 11 of the container and forming a water-tight joint to prevent leakage from the tank. The wall 25 is suitably apertured, as shown at 29, to permit the water resulting from the melting 75 of the ice to reach the drain openings 19. 80

Suitable means are provided for withdrawing the water from the tank. As shown a siphon arrangement is employed. One leg of the siphon is carried by the tank and one by the container. The two legs are connected together by an air-tight joint and the members of the joint are so arranged that they may be readily disconnected. Preferably the arrangement is such that the parts are disconnected in the act of removing the 90 tank from the container. In the form selected to illustrate the invention the inner end of the draw-off pipe 14 extends upwardly through the container bottom 11 and terminates in a tapering nipple 30, which receives, as a slip joint, the downturned end 31 of a siphon tube 32 which extends through the wall of the tank 20 and downwardly to close proximity with the bottom 26 thereof. Suitable packing 30^a between the parts of 95 the slip joint forms an air-tight connection in the longer leg of the siphon. The bow of the siphon tube 32 is well toward the top of the tank, as shown approximately one-third of the length of the tank from its upper end. 100

When the tank 20 is placed within the container, the downturned end of the pipe 32 being inserted into the nipple 30, tight joints are automatically secured at this 105 110 nip-

ple and at the nipple 27. The tank being now filled with water, the draw-off siphon is primed as soon as the level of the bow is reached, and the tank may be entirely 5 emptied of its contents through the faucet 17.

The cover 24 being replaced after the tank is filled, the ice container may be charged without danger of contamination of the 10 water, and no seepage into the tank from the container can occur.

For clearing the tank may be lifted out of the container, the lifting action automatically breaking the joints at 27 and 30, and permitting the water to be drained from the tank through the outlets 19, and in performing the cleaning operation there is no 15 possibility of contaminating the water, which may remain in the draw-off tube 14.

20 The device is not only simple of construction and operation, but is perfectly sanitary.

While a preferred form of construction is shown and described, various changes of detail may be made without departing from 25 the scope of the invention.

I claim as my invention—

1. A water cooler comprising, in combination, an ice container, a water tank enclosed within the container, and a siphon draw-off 30 tube leading from the tank, said tube including sections, means for connecting said sections whereby the same are disconnected by the removal of said tank from said container.

2. A water cooler comprising, in combination, an ice container, a water tank enclosed within the container, and a two-part siphon tube leading from the tank, one section of 35 this tube being attached to the container

and the other section being attached to the tank, the two sections being united by a slip joint. 40

3. A water cooler comprising, in combination, an ice container, a water tank enclosed 45 within the container, the bottom of the tank being provided with an aperture adapted to receive and be sealed by a plug on the bottom of the container when the parts are assembled, and a draw-off tube leading from the tank independent of its named bottom 50 opening.

4. In a water cooler, in combination, an ice container having a normally open drip opening at its lower end, a water tank within the container, a siphon draw-off tube 55 leading from the tank, the longer leg of the siphon being outside of the tank and comprising two sections united by a slip joint.

5. In a water cooler, in combination, an ice container having a normally open drip 60 opening at its lower end, a water tank within the container, a siphon draw-off tube leading from the tank, the longer leg of the siphon being outside of the tank and comprising two sections united by a slip joint, 65 the tank having a drain opening in its bottom, and a plug fixed to the bottom of the container for closing the opening when the tank is positioned in the container.

6. A water cooler comprising, in combination, an ice container, a water tank enclosed 70 within the container, and a two-part siphon tube leading from the tank, one section of this tube being attached to the container and the other section being attached to the tank, 75 the two sections being united by a separable joint.

ROYAL E. MILLER.
